CLAIM

The ornamental design for an in-line mixer, as shown and described.

DESCRIPTION

FIG. 1 is a perspective view of an in-line mixer showing my new design, as viewed from a first end thereof.

FIG. 2 is another perspective view of the in-line mixer, as viewed from a second end thereof.

FIG. 3 is a first side view of the in-line mixer.

FIG. 4 is a second side view of the in-line mixer that is 90-degrees to the first side view in FIG. 3.

FIG. 5 is a third side view of the in-line mixer that is 90-degrees to the second side view in FIG. 4.

FIG. 6 is a fourth side view of the in-line mixer that is 90-degrees to the third side view in FIG. 5.

FIG. 7 is an end view of the first end of the in-line mixer.

FIG. 8 is an end view of the second end of the in-line mixer.

FIG. 9 is the perspective view of the in-line mixer in FIG. 2 having environmental structure depicted in cross-section; and,

FIG. 10 shows the first side view of the in-line mixer in FIG. 3 having environmental structure depicted in cross-section.

The broken line showing of environmental structure in FIGS. 9 and 10 is for illustrative purposes only and forms no part of the claimed design.
